METHOD OF OPERATING A CUPOLA FURNACE

Filed May 4, 1931

FIG.1.

FIG. 2.

FIG. 3.

INVENTOR:
VOTAW S. DURBIN.

By *Bruce S. Elliott*

ATTORNEY.

UNITED STATES PATENT OFFICE

VOTAW S. DURBIN, OF ST. LOUIS, MISSOURI

METHOD OF OPERATING A CUPOLA FURNACE

Application filed May 4, 1931. Serial No. 534,756.

This invention relates to certain new and useful improvements in the method of operating a cupola furnace described and claimed in my prior Patent No. 1,778,524, dated October 14, 1930.

In said prior patent the cupola furnace is provided with two sets of tuyères at its lower end, located at different heights, and the method consists broadly, in first running one heat with the upper set of tuyères closed and then, without removing the remaining slag, running additional heats with the lower set of tuyères closed and the upper set of tuyères open.

15 This method of operating a cupola furnace has been in actual use for approximately two years, and is still in use, and it presents all of the advantages, outlined in the specification of said patent, as compared with the conventional method of running a single heat and thereafter dropping the bottom of the furnace to remove the slag.

It was discovered, however, that after the second heat and at the beginning of the third heat, it was often impossible to force air through the upper set of tuyères in quantity sufficient to supply the requisite amount of oxygen. This was due to the fact that during the preceding heats a certain amount of slag 25 would collect about the tuyères and "freeze," or harden, with the result that the openings were greatly reduced in size, and the air blast correspondingly reduced in capacity. As a result the molten metal would be relatively 30 "cold" and sluggish.

It has been found, in practice, to be impracticable, therefore, to run more than two or three heats without dropping the bottom of the furnace to remove the accumulated 35 slag. This, while representing a decided advantage over the prior practice of dropping the bottom after each heat, still did not yield the maximum advantages which, in principle, is capable of being attained by following the broad principle of operation set forth in my said prior patent.

According to the present invention, I overcome the disadvantage alluded to by providing a number of sets of tuyères arranged in 50 superposed relation, and operating these

tuyères in stages beginning with the lower set and ending with the upper set, and thereby, in operation, gradually raising the height of the heating zone, so that the requisite heat for melting can always be maintained, and the necessary amount of oxygen supplied by the air blast.

The operation, and the advantages thereof, may be more clearly understood from the detail description to follow.

In the accompanying drawing, which illustrates the arrangement of the tuyères of a cupola furnace which I employ in practicing my method—

Figure 1 is a view in elevation of the lower part of a cupola furnace provided with four sets of tuyères arranged according to my invention; and

Figure 2 is a sectional view through one of the tuyères, taken on the line 2—2 of Figure 1.

Figure 3 is a view in broken elevation showing a modified arrangement of the tuyères.

Referring now to the drawing, the numeral 1, indicates the body of the furnace which, near the bottom, is provided, as usual, with a circular drum 2. In the present instance, drum 2 encloses three sets of superposed, circular series of tuyères 3 formed in the wall 4 of the body 1, and one of which tuyères is shown in Figure 2. Opposite each of the tuyères 3 the wall of drum 2 is provided with openings 5 opposite, or in alignment with the opening 3, each opening 5 being normally closed by a door 6, which may be opened to permit the operator to open or close the corresponding opening 3. These openings are usually closed by tamping clay into them, and are opened by inserting an iron bar through each opening 5 and removing the clay from the corresponding openings 3.

Below the drum 2 the furnace is provided with the conventional set of tuyères, each opposite a duct 7, which are connected to and communicate with the drum 2, through the bottom thereof, by means of air pipes 8, and the air blast is applied to the drum 2 by means of a pipe 9, leading from the blower, as usual.

As indicated, I preferably employ four sets of tuyères, and for convenience in following

the description of the operation now to be given, these sets of tuyères are indicated, respectively, at the left of Figure 1, by the letters A, B, C and D, the letters being arranged in order opposite each circular set of tuyères, beginning at the bottom.

I may state that in practice I find it desirable to provide a less distance between the sets of tuyères C and D than between the sets of tuyères B and C. This modified arrangement is illustrated in Figure 3, where the corresponding sets of tuyères are indicated by the letters B', C', D'.

In operation, the furnace being charged, the three sets of tuyères B, C and D closed, 15 and the set of tuyères A opened, the bed of fuel at the bottom of the furnace is ignited and supplied with a forced draft passing through pipe 9 into the drum 2, through air pipes 9, and then through tuyères A. This is 20 the ordinary operation. After the metal in the furnace has been melted, it is run out of the furnace through the discharge opening from the furnace, indicated by the numeral 10. This operation concludes the first heat, 25 and at its conclusion, the tuyère-openings at 7 are closed, and if desired, a considerable time may be permitted to elapse before running the second heat.

In running the second heat, the tuyères A 30 are first closed and the tuyères B opened, and the furnace having been freshly charged, the forced draft is applied as before, the air now passing through the tuyères B. The second heat and sometimes the third, can usually be completed with the use of the tuyères B only, and after the molten metal has been discharged from the furnace, the set of tuyères C are opened by removing the clay from their 35 holes 3, and the next heat is started, with the blast passing through the tuyères B and C.

The next heat, and one or more succeeding heats, may be run in the same manner,—that is, with the blast passing through the tuyères B and C. If it is found, however, that slag from the preceding operation has closed the tuyères B and C to an extent to impair the efficiency of the blast, the tuyères D may be 45 opened and succeeding heats run with the blast passing through the sets of tuyères B, C, and D, or the sets of tuyères C and D, should the tuyères B become completely closed.

It will be understood that it is only necessary to close the tuyères A after running the 55 first heat, as in running the subsequent heats the molten metal will never rise sufficiently high in the furnace to run out of the tuyères B.

It will further be understood that the opening of the tuyères C and D is not necessarily coincident with the starting of a heat, as these tuyères are only opened, in the order named, when it is found that the series of tuyères 65 below them have become so clogged with slag

as to render the admission of a stronger blast to the furnace necessary.

From the above description of the operation, it will be seen that, as each set of tuyères is opened, the zone of heat in the furnace will 70 be correspondingly raised, with the result that the metal above the freshly opened set of tuyères will be preheated, as it were, so that by the time the molten metal has reached the bottom of the furnace it will be in a more 75 highly-heated condition than if the blast had been applied only in the zone of the lowest set of tuyères, or in the one immediately above it.

As a result of my novel method of procedure, a cupola furnace may be continuously operated to run quite a large number of heats, the only interruption that may occur in the operation being that involved when the furnace is recharged, although usually the furnace is continuously charged as the metal is melted.

While my invention may be utilized to advantage in operating any cupola furnace, its highest advantages are derived when the cupola furnace is used in melting metal for making malleable iron castings, and is operated in conjunction with an air furnace for receiving the molten metal for further heating direct from the cupola furnace. By this 90 arrangement, while the charge delivered to the air furnace is being highly heated preliminary to being run into the molds, the cupola furnace can be recharged, or the charging thereof continued, and fresh metal 100 be run into the air furnace as desired, some or all of the metal in which latter has in the meantime been run into the molds.

I claim:

1. The method of operating a cupola furnace which consists in first running a heat in conventional manner, then closing tuyères of the furnace employed in running said heat, and without removing the remaining slag, running successive heats, and from time to time during the running of the heats applying blasts to said furnace at successively higher points therein.

2. The method of operating a cupola furnace which consists in running a heat with blast applied at the lower end of said furnace, then closing the blast openings, and without removing the remaining slag, running additional heats by applying blasts to the furnace first in a single zone above said closed openings and then, at will in a plurality of zones located at successively increasing heights in the furnace.

3. The method of melting metal in a cupola furnace having a plurality of sets of tuyères at its lower end located at different heights, which consists in running the first heat with only the lower set of tuyères open, then, without removing the remaining slag, closing said tuyères and running another 125

heat with only the second set of tuyères open, and running additional heats with the two lowest sets of tuyères in the condition last described, and from time to time opening additional sets of tuyères, in order, above said second set.

4. The method of melting metal in a cupola furnace having three or more sets of tuyères at its lower end located at different heights, which consist in first running a heat with the lowermost set of tuyères open and all the other tuyères closed, then, without removing the remaining slag, running another heat with the lower set of tuyères closed and the set immediately above it open, running additional heats with the two lowest sets of tuyères in the condition last described, and from time to time opening additional tuyères above the two lowest sets of tuyères.

5. The method of operating a cupola furnace which consists in first running a heat with blast applied through conventional tuyères in the lower end of the furnace, closing said tuyères and thereafter, without removing the remaining slag, running additional heats, and during the running of said heats gradually increasing the height of the heating zone in the furnace by successively applying blasts thereto at zones of application gradually increasing in height from the bottom of the furnace.

6. The method of operating a cupola furnace which consists in first running a heat with the blast applied through conventional tuyères in the lower end of the furnace, closing said tuyères and thereafter, without removing the remaining slag, running additional heats, and during the running of said heats gradually increasing the height of the heating zone in the furnace by successively applying blasts thereto at zones of application gradually increasing in height from the bottom of the furnace, the blast in each new zone of application supplementing a preceding blast.

In testimony whereof, I have hereunto set my hand.

VOTAW S. DURBIN.
